D. W. CAMERON.
RAIL JOINT AND CHAIR.
APPLICATION FILED JAN. 7, 1911.

1,006,719.

Patented Oct. 24, 1911.

UNITED STATES PATENT OFFICE.

DANIEL W. CAMERON, OF PITTSBURGH, PENNSYLVANIA.

RAIL JOINT AND CHAIR.

1,006,719.

Specification of Letters Patent. Patented Oct. 24, 1911.

Application filed January 7, 1911. Serial No. 601,842.

To all whom it may concern:

Be it known that I, DANIEL W. CAMERON, citizen of the United States, residing at Pittsburgh, in the county of Allegheny and State of Pennsylvania, have invented certain new and useful Improvements in Rail Joints and Chairs, of which the following is a specification.

This invention relates to an improved rail joint and chair, and has for an object to provide a locking means for the adjoining ends of rails which insures the rigidity of the joint and one which at the same time can be quickly and easily applied to the rails.

The invention further contemplates a safety joint which will not become detached by the breakage of the locking or holding nuts at one side of the same, for instance when the wheels of the rolling-stock leave the track and cut the protruding nuts and the ends of the clamping bolts at one side of the joint releasing the bolts from the joint and permitting the ends of the rails to separate. To obviate this danger this invention provides auxiliary clamping bolts and nuts which are housed and protected so that the flanges of the wheels cannot reach the same.

The invention has for a still further object to provide a comparatively simple and inexpensive joint adaptable to rails now commonly used, whether the rail be of the ball type or of the flange type as is commonly used in street railway construction.

For a full understanding of the invention and the merits thereof and also to acquire a knowledge of the details of construction, reference is to be had to the following description and accompanying drawings, in which:

Figure 1 is a side elevation of the improved joint, partially in section; Fig. 2 is a horizontal section taken through the same. Fig. 3 is a transverse section taken on the line 3-3 of Fig. 1. Fig. 4 is a top plan view of one of the staple bolts detached. Fig. 5 is a transverse central section taken through the joint disclosing a slight modification therein.

Corresponding and like parts are referred to in the following description and indicated in all the views of the drawing by the same reference characters.

Referring to the drawing the reference numerals 10 and 10^a designate the meeting ends of two rails which are secured together

by the improved joint. Each of the rails is provided with a web 10^b supported upon a base flange 10^c of common form. The rails 10 and 10^a are supported upon a chair composed of the side plates 11 and 11^a arranged in registration against the opposite sides of the rails and employed in lieu of the fish plates now used. The plates 11 and 11^a are spaced outwardly from the sides of the webs 10^b of the rails and are turned in at their upper edges; as at 11^b to seat snugly beneath the heads of the rails. As noted from Fig. 3. The lower ends of the plates 11 and 11^a are turned outwardly and engage over and beneath the base flanges 10^c of the rails to provide base plates 11^c and 11^a. The base plate 11^c is provided at its inner edge with a lip 11^e which is formed by reducing the thickness of the inner edge of the base plate by recessing the upper face thereof. The base plate 11^a is provided with a lip 11^f at its inner edge which is formed by recessing the lower face of the base plate 11^c. The lip 11^f overlaps the lip 11^e. The inner opposite faces of the lips 11^e and 11^f are provided with ribs 11^g which interfit when the plates register and hold the same from lateral displacement relative to one another.

The webs 10^b of the rails are apertured as at 10^d in the usual manner, the apertures being disposed in longitudinal registration midway between the bases 10^c and the heads of the rails. Staple bolts 12 and 12^a are arranged in overlapping relation against the opposite sides of the webs 10^b to secure the rail sections together. Each of the staple bolts 12 is formed of a rounded bar bent substantially U-shape and having relatively long and threaded arms 12^b which engage through the openings 10^d of the rails. Inner clamping nuts 13 engage over the threaded arms 12^b of the staple bolts and bind against the webs 10^b between the same and the plates 11 and 11^a. The arms 12^b extend out from the nuts 13 and project through openings formed in the plates 11 and 11^a in registration with the openings 10^d in the rails. Outer clamping nuts 13^a are carried upon the arms 12^b against the outer faces of the plates 11 and 11^a. Staple bolts 12 thus serve the double function of holding the rails 10 and 10^a together and also retaining the chair plates 11 and 11^a in position. At the ends of the plates 11 and 11^a transverse bolts 14 are employed, the same being of common form 11^c

and having clamping nuts 15 upon their outer ends. The bolts 14 are employed for the purpose of binding the ends of the plates 11 and 11^a against the rails. As the staple bolts 12 are arranged in overlapping relation, and as their central portions rest snugly against the opposite sides of the webs 10^b of the rails, such central portions of the staple bolts 12 are arched down to accommodate the arms 12^b of the opposite staple bolts and the inner clamping nuts 13 which are carried thereon. This construction is disclosed to advantage in Fig. 1. In assembling this form of rail joint and chair the staple bolts 12 and 12^a are engaged against the opposite sides of the webs 10^b. The staple bolt 12 is so positioned that one of its arms 12^b engages through the opening 10^d at the extreme inner end of the rail 10 while its opposite arm 12^b engages through the second last opening 12^d formed through the end of the rail 10^a. The opposite and overlapping staple bolt 12^a has one of its arms 12^b positioned through the opening at the extreme end of the rail 10^a, such arm passing over the central portion of the staple bolt 12 at the opposite side of the rail 10^a. The opposite arm 12^b of the staple bolt 12^a engages through the second last opening in the rail 10 beyond the arm 12^b of the staple bolt 12. The central portion of the staple bolt 12^a is arched down beneath the arm 12^b of the staple bolt 12. The inner clamping nuts 13 are now positioned over the arms 12^b to bind the staple bolts 12 and 12^a against the opposite sides of the webs 10^b. The chair plates 11 and 11^a are now engaged against the opposite sides of the rails 10 and 10^a, the lips 11^e and 11^f overlapping to register the ribs 11^g. In positioning the plates 11 and 11^a the arms 12^b of the staple bolts 12 and 12^a engage through the openings in the chair plates. The outer clamping nuts 13^a are now positioned upon the outer extremities of the arms 12^b and are tightened against the outer faces of the chair plates 11 and 11^a. The transverse bolts 14 are now clamped through the plates 11 and 11^a and the webs 10^b of the rails. Should, by accident a wheel leave the rails 10 and 10^a and pass over the outer face of one of the plates 11 or 11^a and cut off the outer clamping nuts 13^a and the extremities of the arms 12^b, the staple bolts 12 would not be released from the rails 10 and 10^a and the rails would be held in position. The arrangement of the staple bolts 12^a and their inner clamping nuts 13 offsets accidents incident to the separating of the rails when the outer clamping nuts are cut off from the joint. The heads of the rails 10 and 10^a protect the inner clamping nuts 13 as they lie snugly against the webs 10^b and cannot be reached by the flange of the wheel which has left the track. This arrangement is had

at both sides of the rails 10 and 10^a so that the joint cannot be severed by the wheel when it falls at either side of the rails.

In Fig. 5 a slightly modified form of the rail joint is disclosed, in which the webs 10^b of the rails are short. In this instance the space between the bases 10^c of the rails and the heads thereof is not sufficient to admit of the positioning of the conventional size of inner clamping nuts and wherein it is necessary to form the inner clamping nuts 13^b with annular grooves 13^c to snugly receive the central portions of the staple bolts 12 and 12^a. The end inner clamping nuts 13^d, which do not have the staple bolts engaging therebeneath, are provided with rounded outer edges 13^e to snugly fit against the inner shoulders formed at the upper edges of the chair plates 11. In this form the outer clamping nuts 13^a are provided with lock or spring washers 15 interposed between the outer clamping nuts 13^a and the outer faces of the chair plates 11. It will be noted that in assembling this modified form of the rail joint that the central portions of the staple bolts 12 must be inserted in the grooves 13^c of the inner clamping nuts 13^b prior to the attachment of the nuts over the arms 12^b of the staple bolts. The staple bolts 12 and 12^a are fed into position through the webs 10^b by the inward movement of the nuts 13^a over the arms 12^b. As these nuts 13^a are interlocked with the central portions of the staple bolts, the staple bolt 12 cannot be withdrawn from the webs 10^b until the nut 13^a of the opposite staple bolt 12^a is released therefrom, and vice versa.

It will be particularly observed from Figs. 1 and 3 of the drawing that the ribs 11^g formed upon the adjacent faces of the overlapping lips 11^e and 11^f provide a plurality of spaced shoulders having inwardly inclined faces adapted to interlock when the plates 11 and 11^a are brought into registration to prevent the pulling of the plates away from the webs 10^b of the rails. It will be noted from Fig. 1 that a depression is formed between contiguous shoulders to receive the shoulder of the overlapping lip when the plates are displaced longitudinally from one another to admit of the separation of the plates when it is desired to open the joint. The chair plates 11 and 11^a are provided with elongated apertures engaging over the arms 12^b to admit of the longitudinal movement of the plates 11 and 11^a against the sides of the rails when interlocking the corrugations 11^g. The slots in the plates are of such length that when the shoulders of the ribs 11^g register the arms 12^b strike the inner ends of the slots and hold the plates from moving past one another.

The clamping bolts 14 are provided with nuts 15^a interposed between the webs 10^b 130

of the rails and the chair plates 11 and 11^a. With the provision of these inner clamping nuts the bolts 14 will not fall from the chair plates 11 and 11^a when the outer clamping nuts 15 are cut, or are otherwise displaced.

Having thus described the invention, what is claimed is:

1. A rail joint including the meeting ends of rails, a pair of overlapping staple bolts 10 engaging against the opposite sides of the rails and engaging across the extremities thereof, said staple bolts being arched downwardly at their central portions to receive the inner arms of the opposite bolts, clamping nuts carried upon the arms of the bolts and binding against the rails, chair plates 15 positioned against the opposite sides of the rails to house the staple bolts, and outer clamping nuts carried by the arms of the 20 staple bolts and resting against the outer faces of the chair plates.

2. A rail joint including the meeting ends of rails, overlapping staple bolts engaging against the opposite sides of the rails and 25 overlapping their meeting ends, chair plates positioned against the sides of the rails to house the staple bolts and having base plates seating beneath the rails, the base plates being provided with overlapping and oppositely corrugated lips adapted to intermesh and hold the base plates from longitudinal 30 displacement, the arms of the staple bolts engaging through the chair plates, inner clamping nuts carried by the arms and binding against the webs of the rails, and outer clamping nuts engaging against the outer 35 faces of the chair plates.

3. A rail joint including the meeting ends of rails, plates engaging against the opposite sides of the rails, bolts carried through the webs and the plates and having their ends extending oppositely therethrough, said plates being spaced from the sides of the rails, inner clamping nuts carried upon the 40 bolts against the webs of the rails, and outer clamping nuts carried upon the bolts against the outer faces of the plates.

4. A rail joint including the meeting ends

of rails, U-shape bolts overlapping against the opposite sides of the rails and having 50 their threaded arms engaging therethrough, the central portions of the U-bolts being offset to receive the arms of the opposite bolt, and clamping nuts disposed upon the threaded extremities of the bolts for binding engagement against the sides of the 55 rails.

5. A rail joint including the meeting ends of rails, U-shape bolts engaging in overlapping relation against the opposite sides of the 60 rails and having their central portions offset to accommodate the arms of the opposite bolts, clamping nuts carried upon the arms of the bolts and engaging snugly against the sides of the rail, fish plates 65 engaging against the sides of the rails and having their central portions spaced slightly therefrom to accommodate the clamping bolts, the extremities of the bolts passing through the fish plates, and outer 70 clamping nuts carried upon the bolts and engaging against the outer sides of the fish plates.

6. A rail joint including the meeting ends of the rails, overlapping U-bolts engaging 75 against the opposite sides of the rails and being offset at their central portions to receive the arms of the opposite bolts, fish plates carried against the sides of the rails and being spaced slightly therefrom to accommodate the central portions of the U-bolts, the arms of the U-bolts extending 80 through the fish plates and being threaded throughout their lengths, inner clamping nuts carried upon the arms and engaging 85 against the webs of the rails, and outer clamping nuts carried upon the arms of the U-bolts and binding against the outer faces of the fish plates.

In testimony whereof, I affix my signature in presence of two witnesses.

DANIEL W. CAMERON. [L.S.]
